UNITED STATES PATENT OFFICE.

CHRISTIAN F. SAUEREISEN, OF WEST VIEW, PENNSYLVANIA.

STRAIN-INSULATOR SIGN.

1,381,594.

Specification of Letters Patent. Patented June 14, 1921.

Application filed May 28, 1919. Serial No. 300,383.

To all whom it may concern:

Be it known that I, CHRISTIAN F. SAUEREISEN, a citizen of the United States, and a resident of West View, in the county of

5 Allegheny and State of Pennsylvania, have made a new and useful Invention in Strain-Insulator Sign, of which the following is a specification.

In power line transmission, charged wires 10 are often upheld by supporting wires attached to poles. This necessitates the use of insulating means to prevent the grounding of the current. A familiar illustration of this is the support of trolley wires by cross 15 wires to poles located at the street curb. The circuit may be broken by dividing the supporting wire between the trolley wire and each pole and securing the divided parts to an insulator so that the wires have no contact with each other. This is in addition to 20 any other insulating means between the trolley wire and supporting wire.

Signs indicating voltage, danger, location 25 of car stops, circuit breaks and other information are commonly used in connection with power lines and are formed of metal or wood panels and means securing same to the pole or wire and are very likely to be near to the point where a strain insulator is 30 attached.

My invention consists of a connecting unit for oppositely pulling wires combining the 35 functions of connecting and insulating the contiguous wires and giving any desired information. It may be manufactured of glass, porcelain, wood or other insulating material and may be of any suitable shape. A preferred form is illustrated in the drawing forming a part of this specification in 40 which Figure 1 is a side elevation of my strain insulator; Fig. 2 is a section through same on line 2--2 of Fig. 1 and Fig. 3 illustrates its application to a trolley line for street cars.

45 The body 4 of the insulator is provided with a vertical hole 5 and extending from the ends of this hole are grooves 10 on the top and bottom of the body. Horizontal

holes 6, spaced from each other and from hole 5, extend through body 4 and one pair 50 of adjacent ends of holes 6 are connected by a groove 11.

Hole 5 and grooves 10 are adapted to accommodate the looped end of a wire such as wire 7 in Fig. 3. Holes 6 and groove 11 are 55 similarly adapted for the looped end of an opposing wire such as wire 8 in Fig. 3. Each wire will be securely held spaced from the other so there can be no contact between them. 60

Integral with body 1 are flanges 9 of a shape and size adapted to bear words of notice or advertisement which may be read at sufficient distance to serve a useful purpose. I prefer to engrave the letters of the sign 65 in the flange face and coat the engraved letters with enamel.

I have shown two opposite flanges in the preferred form of my invention but when applied as shown in Fig. 3 only one flange 70 would be necessary. Obviously, any number of these flanges could be used at various angles to each other and either above or below as well as at the sides of the body of the insulator. 75

This device may be manufactured more economically than the separate articles now used for the same purposes, it reduces the expense of installing and it avoids metallic hangers, or other attaching means as used 80 on ordinary signs, which are subject to corrosion, electrolysis and other disintegrating influences.

I claim:

An article of manufacture comprising a 85 block of insulating material adapted to serve as an insulating connection for wire terminals and provided with integral letter bearing flanges of substantially larger dimensions than the thickness of said block and 90 spaced from said block.

In testimony whereof, I have hereunto subscribed my name this 8th day of April, 1919,

CHRISTIAN F. SAUEREISEN.
